PROCESS FOR RESOLVING PETROLEUM
EMULSIONS

Melvin De Groote, University City, and Arthur F. Wirtel, Kirkwood, Mo., assignors, by mesne assignments, to Petrolite Corporation, Ltd., a corporation of Delaware

No Drawing. Application December 21, 1938,
Serial No. 247,002

7 Claims. (Cl. 252—336)

This invention relates primarily to the treatment of emulsions of mineral oil and water, such as petroleum emulsions, for the purpose of separating the oil from the water.

5 One object of our invention is to provide a novel process for resolving petroleum emulsions of the water-in-oil type, that are commonly referred to as "cut oil," "rolly oil," "emulsified oil," etc., and which comprise fine droplets of naturally-occurring waters or brines dispersed in a more or less permanent state throughout the oil 10 which constitutes the continuous phase of the emulsion.

Another object of our invention is to provide an 15 economical and rapid process for separating emulsions which have been prepared under controlled conditions from mineral oils, such as crude petroleum and relatively soft waters or weak brines. Controlled emulsification and subsequent 20 demulsification under the conditions just mentioned is of significant value in removing impurities, particularly inorganic salts, from pipeline oil.

The demulsifying agent employed in our process 25 is a new compound or composition of matter consisting of a certain kind of salt derived from a surface-active esterified amine of the kind hereinafter described and an alkylated naphthalene sulfonic acid of the kind in which there is at least one alkyl group substituted in the naphthalene nucleus, the said alkyl group or groups in 30 turn being characterized by containing at least three carbon atoms and not more than ten carbon atoms.

Said alkylated sulfonic acid can be described 35 by the following formula:

in which n indicates any small whole number, such as 1, 2, or 3; but generally speaking, the 40 monosulfonic acid would be employed, and for purposes of brevity, the formula $D.SO_3H$ will be used.

It is well known that certain monocarboxy organic acids containing approximately eight carbon atoms or more and not more than 32 carbon atoms, are characterized by the fact that they combine with alkalis to produce soap or soap-like materials. These detergent-forming acids include fatty acids, halogenated fatty acids, resin acids, hydrogenated resin acids, petroleum acids,

chlorophenolic acids, etc. For sake of convenience, these acids will be indicated by the formula $R.COOH$.

It is known that basic compounds may be produced from detergent acids, or esters thereof, and 5 monoalkylamines, such as monoethanolamine, which are characterized by the following formula:

Similarly, one can produce materials of the type 10 indicated by the following formulas:

Needless to say, in the above formulas where an 15 amino hydrogen atom appears, it may be replaced by some suitable substituent, such as an alkyl radical, alicyclic radical, etc. Such amines, containing the esterified detergent-forming acid radical, are surface active in either hydrophobic or hydrophilic solvents, and especially after neutralization with acids such as HCl .

If a surface-active amine of the kind above described is used to neutralize an alkylated aromatic acid of the kind typified by the formula $D.SO_3H$, then one obtains complex salts characterized by 25 having both a surface-active anion and a surface-active cation; and these salts may be illustrated by the following formulas:

The actual composition of the above type of material may be more clearly expressed by the 35 following formula which is another form of the particular preceding formula, in which an esterified primary basic amine is employed for neutralization:

Having indicated in a general way the nature of the new compound or composition of matter employed as the demulsifier in our process, it is deemed desirable to indicate the method of producing or manufacturing the surface-active amine of the kind which is employed to neutralize the alkylated naphthalene sulfonic acid previously referred to, and also to indicate the variety 45 of such amines that may be utilized.

50

Reference is made to co-pending application for patent Serial No. 180,993, filed December 21, 1937, by Melvin De Groote, Bernhard Keiser and Charles M. Blair, Jr.

5 If triethanolamine, employed in the above formula, is replaced by ethyl diethanolamine, then one would obtain one of the remaining types of tertiary amines illustrated. Reference is made to Patent No. 2,167,349, dated July 25, 1939, to De Groote, Keiser, and Blair.

10 In the remaining type of material there is an amino hydrogen atom present. The manufacture of such material may be illustrated by the following reactions:

25 However, if maximum yields are not necessary, one need not resort to reactions of the kind previously described to produce secondary amines, but one may employ the following type of reaction:

55 Suitable primary and secondary amines, which may be employed to produce materials of the kind above described, include the following: diethanolamine, monoethanolamine, ethyl ethanolamine, methyl ethanolamine, propanolamine, dipropanolamine, propyl propanolamine, etc. Other examples include cyclohexylolamine, dicyclohexylamine, cyclohexyl ethanolamine, cyclohexyl propanolamine, benzylethanolamine, benzylpropanolamine, pentanolamine, hexanolamine, octylethanolamine, octadecylethanolamine, cyclohexanolethanolamine, etc.

60 Similarly, suitable tertiary amines which may be employed include the following: triethanolamine, diethanolalkylamines, such as diethanol ethylamine, diethanol propylamine, etc. Other examples include diethanol methylamine, tripropanolamine, dipropanol methylamine, cyclohexanol diethanolamine, dicyclohexanol ethanolamine, cyclohexyl diethanolamine, dicyclohexyl ethanolamine, dicyclohexanol ethylamine, benzyl diethanolbenzyl dipropanolamine, tripentanolamine, trihexanolamine, hexyl ethanolamine, octadecyl diethanolamine, polyethanolamine, etc.

It is also known that one may have amines of the type:

Such amines may serve as the obvious functional equivalents of the previously described amines and which are free from an ether linkage.

All of the amines of the kind above described and characterized by the formula:

25 have four common characteristics. In the first place, these amines are not quaternary ammonium bases or salts thereof. The expression "quaternary ammonium" is properly and conventionally applied to compounds in which all four hydrogen atoms of the ammonium radical NH_4^+ have been replaced by a hydrocarbon radical or oxy-hydrocarbon radical, as, for example, in trimethyl phenyl ammonium hydroxide.

30 Secondly, an important characteristic which must be recognized is, that these amine com- 35

35 pounds are not amides. It is to be noted that an amide formation involves a product in which there is a direct linkage between the carboxylic carbon atom and the nitrogen atom in the amine. 55 This is not the case in the compounds employed as intermediate raw materials for production of the compounds used as demulsifying agents in the present process.

40 In the third place, it must be recognized that 60 these compounds are derived only from basic amines. The word "basic" is employed to exclude amines having little or no basicity, such as the ordinary aromatic amines, or any amine having at least one aryl radical directly joined to the amino nitrogen atom. For this reason, these amine products which are herein contemplated as demulsifying agents, and which necessarily are characterized by freedom from any aryl groups as such, cannot be derived from aryl amines. They are derived solely from alkyl, 65 alicyclic, or aralkyl amines having at least one hydroxyl group present. It is true that in the aralkyl amines there is an aryl group present, but it is not directly attached to the nitrogen atom, as 70 75

in the case of aryl amines, but in fact, represents nothing more or less than a substituted alkylamine. For instance, we consider benzylamine as being the primary amine, phenethyl amine,

5 Finally, it must be recognized that these materials have not lost any basicity in the forms of the esterified amine, and that they exhibit all the properties of a basic amine, that is, they combine with water to form a base, presumably a substituted ammonium compound, but not quaternary ammonium compound, insofar that there are always one, two, or three unsubstituted hydrogen atoms of the ammonium radical present. They combine with various acids to form salts.

10 For example, they may be combined with acetic acid, hydrochloric acid, lactic acid, chloracetic acid, nitric acid, butyric acid, phosphoric acid, oxalic acid, or any suitable organic or inorganic acid, to form salts.

15 Reference is again made to the formula which summarizes the various amines used as intermediate raw materials viz.:

in which the characteristics have their previous significance. Attention is directed to the fact that where the substituted alkyl radical

35 appears, a suitable non-aryl radical other than an aliphatic residue may serve as the functional equivalent; for instance, an alicyclic radical derived from a cyclohexyl radical, or an aralkyl radical derived from a benzyl radical. In other words, in the hereto appended claims references to the C_{n2n} radical as such, or as an alkyl radical or residue, is intended in the broad sense to include the alicyclic radicals or residues, or the aralkyl radicals or residues which are the equivalent thereof. There is no intention to include an aromatic radical where there is a direct linkage between the aromatic nucleus and the amino hydrogen atom, for the reason that such products have little or no basicity and do not have the characteristic properties of the amines previously described.

50 In indicating the various hydroxylated tertiary amines of the non-aryl type which may be employed to produce the amine contemplated as the demulsifying agent of the present process, it is desirable to indicate that amines of the type where a hydroxy acyl radical replaces a hydrogen atom of the hydroxyl radical of the hydroxy tertiary amine, are not included within the broad class of hydroxy tertiary amines, unless there is another hydroxyl radical attached to the usual alkyl radical. For instance, if ethyl diethanolamine is treated with two moles of lactic acid so as to form the dilactyl compound of the following formula:

then it is understood that such materials would not represent a hydroxy tertiary amine within the meaning or scope, as herein employed. If, on the other hand, triethanolamine were treated

with lactic acid, so as to give monolactyl triethanolamine of the following composition:

then such compound would be included, due to the presence of one or more hydroxyl radicals attached to the alkyl radicals. 10

Similarly, in indicating the various hydroxylated primary or secondary amines of the non-aryl type, which may be employed to produce the amine contemplated as the demulsifying agent of the present process, it is desirable to indicate that amines of the type where a hydroxy acyl radical replaces a hydrogen atom of the hydroxyl radical of a hydroxy primary or secondary amine, are not included within the broad class of hydroxy tertiary amines, unless there is another hydroxyl radical attached to the usual alkyl radical. For instance, if ethanolamine is treated with lactic acid so as to form the lactyl derivative of the following formula:

then it is understood that such materials would not represent a hydroxy primary amine within the meaning or scope, as herein employed. The same would be true if the corresponding product were derived from diethanolamine, provided both hydroxy radicals had been esterified with lactic acid. 30

The manufacture of compounds from tertiary amines is relatively simple, because no precautions are necessary to prevent amidification. The selected detergent-forming acid, or ester, as, for example, a fatty oil and the selected hydroxy tertiary amine, are mixed in suitable proportions and heated at some point above the boiling point of water, for instance, 110° C., and at a point below the decomposition point of the amine or the fatty oil, for instance, 180° C., for a suitable period of time, such as two to eight hours. Mild agitation is employed. A catalyst, such as sodium oleate, sodium carbonate, caustic soda, etc., may be present in amounts of about one-half of 1%, or less. It is noted that the fatty acids are employed in this instance, in the form of an ester, to wit, the glyceride, although, as previously pointed out, other functional equivalents can be readily employed with equal facility. It is to be noted that the reactions above described do not take place to any appreciable extent if the fatty acid has been converted into the soap or salt. Such salts are not functional equivalents. As previously indicated, an ester of abietic acid or naphthenic acid might be employed, if desired.

When, however, one is employing a hydroxy secondary amine, precautions must be taken, so that one gets a substantial percentage of products derived by esterification, rather than amidification. Any suitable ester may be employed, but it is often most convenient to employ the glyceride of a fatty acid, for instance, triricinolein. The selected glyceride and the selected hydroxy secondary amine are mixed in suitable proportions and heated at some point above the boiling point of water, for instance, 110° C., and below the decomposition point of the amine or fatty material, for instance, 180° C., for a suitable period of time, such as 4-24 hours. Mild agitation is employed. A catalyst, such as sodium oleate, sodium carbonate, caustic soda, etc., may

be present in amounts of about $\frac{1}{2}\%$, or less. It is to be noted that the fatty acids are present in ester form and not in the form of the free acid, and thus there is no tendency to form the salt to any marked extent; and if conducted at the lower range of reaction temperatures, there is a decided tendency to form the esterification products, rather than the amidification products.

In order to illustrate suitable examples of the amines which may be used as intermediate raw materials for neutralizing alkylated naphthalene sulfonic acids of the kind described, attention is directed to the following examples:

15 *Intermediate amine Example 1*

Castor oil is employed. For the sake of convenience, its molecular weight is considered as being 925. Commercial triethanolamine and castor oil in the proportion of one mole of castor oil and three moles of triethanolamine are heated to a temperature between 150-180° C. for two hours. Mild agitation is employed.

20 *Intermediate amine Example 2*

25 The same procedure is followed as in Intermediate amine Example 1, except that the ratio employed is two moles of the castor oil to three moles of triethanolamine.

30 *Intermediate amine Example 3*

35 The same procedure is employed as in Intermediate amine Example 1, except that the ratio employed is three moles of castor oil to three moles of triethanolamine.

35 *Intermediate amine Example 4*

40 One mole of methyl naphthenate is reacted in the manner previously described with one molecule of triethanolamine.

40 *Intermediate amine Example 5*

45 Diethanolamine is substituted for triethanolamine in Example 4.

45 *Intermediate amine Example 6*

50 Methyl abietate is substituted for methyl naphthenate in Examples 4 and 5, above.

50 *Intermediate amine Example 7*

55 Olive oil is substituted for castor oil in Examples 1, 2, and 3 above.

55 *Intermediate amine Example 8*

60 Ethyl diethanolamine is substituted for triethanolamine in Examples 1, and 2, previously described.

60 *Intermediate amine Example 9*

65 Cyclohexyl diethanolamine is substituted for ethyl diethanolamine in the example immediately preceding.

65 *Intermediate amine Example 10*

70 Benzyl diethanolamine is substituted for ethyl diethanolamine in Example 8 above.

70 *Intermediate amine Example 11*

75 Castor oil (triricinolein) is employed. For convenience its molecular weight is considered as being 925. Commercial diethanolamine and castor oil in the proportion of one mole of castor oil to three moles of diethanolamine, are heated to a temperature of 120-140° C., for about twelve hours. Mild agitation is employed. Loss of basicity is an indication of amidification. Time of esterification may be extended or temperature

lowered or raised, so as to insure maximum esterification, and particularly, so as to produce a product characterized by the presence of one unesterified alkylol radical attached to the amino nitrogen.

5

Intermediate amine Example 12

In the previous examples where castor oil is employed, blown castor oil is substituted therefor. We prefer to use a drastically oxidized castor oil having approximately the following characteristics:

Acid number	13.2 to 25.0	10
Saponification number	230.5 to 274.0	15
Iodine number	43.5 to 55.0	
Acetyl number	164.0 to 192.0	
Hydroxyl value	188.0 to 220.0	
Percent unsaponifiable matter	1.1	
Percent nitrogen	0.0	20
Percent SO_3	0.0	
Percent ash	Trace	

In employing a drastically oxidized castor oil, it is our preference to eliminate carboxylic acidity by means of a conventional esterification process. For instance, in referring to the analyses of the blown oil above, it will be seen that such product contains acidity equivalent to 5-10% of the total saponification value. Such acidity can be removed by esterification with an alcohol, such as methyl alcohol, ethyl alcohol, propyl alcohol, etc. On the other hand, insofar that glycerine is the naturally-occurring alcohol present in most oils and fats, and also insofar that glycerine is non-volatile, it is our preference to add sufficient glycerine to such blown oil and keep it agitated to a temperature of approximately 125-170° C., until carboxylic acidity disappears. Such neutral or completely esterified blown oil is then employed in manufacturing the intermediate amines of the kind above described.

Reference is made to the co-pending applications Serial No. 180,992, filed December 21, 1937, by Melvin De Groot, Bernhard Keiser and Charles M. Blair, Jr.; Serial No. 202,986, filed April 19, 1938, by Melvin De Groot, Bernhard Keiser and Charles M. Blair, Jr.; and Serial No. 208,220, filed May 16, 1938, by Melvin De Groot, Bernhard Keiser and Charles M. Blair, Jr.

50 It has been previously pointed out that the intermediate amines are characterized by the fact that they combine with acids to form salts; for instance, they will combine with acetic acid, hydrochloric acid, sulfuric acid, etc. In the present instance, of course, they are employed to form salts, but only a particular kind of salt, to wit, the one derived by neutralization of an alkylated naphthalene sulfonic acid of the kind described. One isomeric form of an amine is 55 as suitable as another form.

55 Alkylated naphthalene sulfonic acids are produced commercially, and the salts are used for a variety of purposes. They are generally produced from naphthalene, because there does not appear to be any advantage in the use of a naphthalene derivative, such as chlor-naphthalene, alpha and beta naphthol, etc. In other words, one could introduce the sulfonic acid residue and the alkyl residues into a substituted 70 naphthalene, such as chlor-naphthalene, etc., just as readily, perhaps, as in the case of naphthalene. Such simple derivatives, of course, are the chemical equivalent of naphthalene in the manufacture of such sulfonic acids as are em- 75

ployed in the manufacture of the present reagent. It is understood that the word "naphthalene" is hereinafter employed to include these derivatives.

5 The general process of manufacturing the particular salts used to produce the demulsifier employed in our process, consists in converting the naphthalene into either the alpha or beta naphthalene sulfonic acid, or a mixture of the same,
10 or in some instances, into a di- or even a tri-sulfonic acid, or a tetrasulfonic acid, or a mixture of the various types. In most instances, there is no advantage in introducing more than one sulfonic acid residue. In many instances, it
15 is unnecessary to use particular care to prepare either only the alpha sulfonic acid, or either only the beta sulfonic acid, because a mixture in which either one or the other predominates, or a mixture in which the alpha and beta sulfonic acids are present in approximately equal amounts, is just as satisfactory as one sulfonic acid completely freed from the other type.

The alcohol employed, such as propyl alcohol, a butyl alcohol, an amyl alcohol, a hexyl alcohol, a decyl alcohol, etc., is converted into the acid sulfate, such as propyl hydrogen sulfate. The naphthalene sulfonic acid and the alkyl hydrogen sulfate are combined in proportions so that one, two, three, or even four alkyl groups are introduced into the aromatic residue. This condensation reaction is generally carried out in the presence of an excess of sulfuric acid. In some instances, the various reactions, such as sulfonation, sulfation, condensation, etc., are carried out simultaneously. Generally speaking, the dialkylated and tri-alkylated material appear to yield the most desirable type of reagent. The presence of some mono-alkylated material, or some tetra-alkylated material is not objectionable, and may even be desirable.

It is obvious, of course, that the alkylated groups introduced might be derived from olefines, such as butylene, propylene, amylene, etc., insofar that such olefines react directly with sulfuric acid, to produce the alkyl hydrogen sulfates. Of course, in addition to introducing such alkyl residues of the kind described, into the aromatic nucleus, one could also introduce an alkyl residue from some other alcohol, as, for example, an alkylated group derived from ethyl or methyl alcohol, or one might introduce a group derived from an aryl, aralkyl, cyclic, or hydroaromatic alcohol, or the like, but regardless of whether or not one introduces such other residues, it is necessary that at least one alkyl residue of the kind described, i. e., having at least three carbon atoms and not more than ten carbon atoms, be introduced into the naphthalene ring. Such compounds having some other group present, such as methyl group, might be considered as being derived from methyl naphthalene, instead of naphthalene, and thus, would fall within the class of chemical equivalents previously noted. It is immaterial as to the particular alcohol employed, or the particular isomeric form of the alcohol employed, although generally speaking, it is most desirable to use the one lower in cost. It is immaterial whether one uses normal propyl alcohol or isopropyl alcohol. It is immaterial whether one uses a normal butyl or isobutyl alcohol. It is immaterial whether the alcohol be a primary alcohol, or a secondary alcohol, or a tertiary alcohol, or the like.

75 It is obvious that a large number of isomers

can be produced in the manufacture of the reagent employed as the demulsifier in the present process. For instance, although the sulfonic group may be introduced into either the alpha or beta position, it is manifest that the alkyl group or groups can be introduced into various positions in regard to the position of the sulfonic acid residue. Apparently, as far as we are aware, one isomeric form is as effective as the other. Reference to the compounds is not intended to indicate any particular isomer, unless the text clearly indicates some specific position.

Insofar that the most readily available alcohols, from the standpoint of cost, are isopropyl alcohol, normal butyl alcohol, isobutyl alcohol, and amyl alcohol, it is our preference to produce our reagents from these alcohols, and in some instances, it is desirable to introduce different alkyl groups, such as a propyl group and butyl group, into the same sulfo-naphthalene residue. 15 20

In the actual manufacture of alkylated naphthalene sulfonic acids, the composition of the desired chemical reaction is followed by a washing process which removes the excess of sulfuric acid or other sulfonation, sulfation, or condensation reagent employed. The acidic mass thus obtained is neutralized in any convenient manner with any suitable base, such as caustic soda, caustic potash, ammonium hydroxide, and the like. However, in accordance with what has been said herein, the acidic mass is neutralized with the amine of the kind previously described. The final product, if it represents a pasty or semi-solid or solid mass, is rendered suitable for industrial use by the addition of a solvent such as water and alcohol, a coal tar solvent, a petroleum hydrocarbon solvent, or the use of any other suitable solvent, such as a phenolic body, or a chlorinated hydrocarbon.

In manufacturing or producing the demulsifier above described, we prefer to obtain a chemical compound by reaction so conducted that three molecules of isopropyl alcohol are united with one molecule of naphthalene by the customary sulfation, sulfonation, and condensation reactions. The resulting mixture consists largely of di-propyl naphthalene sulfonic acids and tri-propyl naphthalene sulfonic acids, with possibly small amounts of mono-propyl sulfonic acids and tetra-propyl sulfonic acids present. Generally speaking, it is easier to conduct the reaction so that the bulk of the sulfonic acid represents the beta type, although the alpha type may be produced, if desired. The product is neutralized with a complex amine of the kind typified by Examples 1, 2, 3 or 12, previously described. The product so obtained is diluted with one or more solvents, so as to reduce its viscosity to that of ordinary castor oil, or slightly greater. The solvents which we preferably employ are a mixture of two or more of the following: Water, denatured alcohol, kerosene, or tar acid oil.

Among the reagents which are particularly effective are the salts formed by reaction between amines of the kind exemplified by Examples 1-12, inclusive, above, and the following alkylated naphthalene sulfonic acids, i. e., mono-isopropyl naphthalene sulfonic acids, di-isopropyl naphthalene sulfonic acids, tri-isopropyl naphthalene sulfonic acids, mono-normal butyl naphthalene sulfonic acids, di-normal butyl naphthalene sulfonic acids, mono-isobutyl naphthalene sulfonic acids, di-isobutyl naphthalene sulfonic acids, mono-amyl naphthalene sulfonic acids, di-amyl naph-

thalene sulfonic acids, tri-⁵amyl naphthalene sulfonic acids, mono-hexyl naphthalene sulfonic acids, di-hexyl naphthalene sulfonic acids, tri-hexyl naphthalene sulfonic acids, mono-octyl naphthalene sulfonic acids, di-octyl naphthalene sulfonic acids, di-decyl naphthalene sulfonic acids, mono-isopropyl di-normal butyl naphthalene sulfonic acids, di-isopropyl di-normal butyl naphthalene sulfonic acids, di-isopropyl mono-amyl naphthalene sulfonic acids, mono-isopropyl mono-hexyl naphthalene sulfonic acids, etc.

In such instances where there is present more than one sulfonic acid radical, as in the formation of a disulfonic acid, or a trisulfonic acid, or a tetrasulfonic acid, if desired, all the sulfonic radicals may be neutralized with amines of the kind previously described, or some of the sulfonic acid radicals may be neutralized with some other suitable base, such as a sodium hydroxide, potassium hydroxide, ammonium hydroxide, etc., provided that at least one sulfonic acid radical has been neutralized by amines of the kind previously described.

Conventional demulsifying agents employed in the treatment of oil field emulsions are used as such, or after dilution with any suitable solvent, such as water, petroleum hydrocarbons, such as gasoline, kerosene, stove oil, a coal tar product, such as benzene, toluene, xylene, tar acid oil, cresol, anthracene oil, etc. Alcohols, particularly aliphatic alcohols, such as methyl alcohol, ethyl alcohol, denatured alcohol, propyl alcohol, butyl alcohol, hexyl alcohol, octyl alcohol, etc., may be employed as diluents. Miscellaneous solvents, such as pine oil, carbon tetrachloride, sulfur dioxide extract obtained in the refining of petroleum, etc., may be employed as diluents. Similarly, the material or materials employed as the demulsifying agent of our process may be admixed with one or more of the solvents customarily used in connection with conventional demulsifying agents. Moreover, said material or materials may be used alone or in admixture with other suitable well known classes of demulsifying agents, such as demulsifying agents of the modified fatty acid type, complex amine type, the petroleum sulfonate type, the alkylated sulfo-aromatic type, neutralized in the conventional manner, or even un-neutralized.

Incidentally, neutralization of the alkylated sulfonic acid with the complex amine need not necessarily take place in stoichiometrical relationship, but one may employ an excess of the sulfonic acid or of the amine. Incidentally, salts of the kind herein contemplated need not be made by direct neutralization, but of course can be produced just as effectively by some other means. For instance, a double decomposition reaction may be utilized, i. e., the amine hydrochloride and the sodium or potassium salt of the sulfonic acid might each be dissolved in a hydrophobe solvent, such as an alcohol and mixed with the separation of sodium or potassium chloride, which could be filtered off and the alcohol evaporated, so as to leave the amine salt of the kind desired.

Attention is directed to the fact that the word "amidification" has been applied to the reaction involving the replacement of amine hydrogen atom by an acyl radical, without conventional limitation to a reaction involving ammonia. The replacement of the amino hydrogen atom of a primary amine or a secondary amine by an acyl radical, has been considered as being amidifica-

tion, rather than the formation of a substituted amide, or the formation of an imide or substituted imide. Such obvious departure from conventional nomenclature has been for purposes of simplicity and to show the similarity between certain reactions.

It is well known that conventional demulsifying agents may be used in a water-soluble form, or in an oil-soluble form, or in a form exhibiting both oil and water solubility. Sometimes they may be used in a form which exhibits relatively limited water solubility and relatively limited oil solubility. However, since such reagents are sometimes used in a ratio of 1 to 10,000, or 1 to 20,000, or even 1 to 30,000, such an apparent insolubility in oil and water is not significant, because said reagents undoubtedly have solubility within the concentration employed. This same fact is true in regard to the material or materials employed as the demulsifying agent of our process.

As has been indicated previously, in essence, we have discovered that if a suitable alkylated naphthalene sulfonic acid is neutralized with an amine of the kind described, one obtains an unusual reagent, to wit, one characterized by having both a surface-active anion and a surface-active cation; and we have furthermore discovered that such reagent is of unusual effectiveness for breaking oil field emulsions. As far as demulsification is concerned, there does not appear to be any suitable explanation of this unusual superiority; and similarly, there does not seem to be any basis by which one could anticipate or foresee this unusual effectiveness. Apparently, this marked improvement is not directly related to oil or water solubility, insofar that similar neutralization with other amines may yield compounds which have a greater solubility in oily materials or in water, and yet are not nearly as suitable and not nearly as effective in their demulsifying action.

Apparently there is some unlooked-for co-operation or chemical or physical-chemical relationship between the complex amine residue and the sulfo-aromatic residue. The neutralization of other conventional acidic demulsifying agents with these amines does not seem to produce nearly as marked improvement over the corresponding sodium ammonium salts, and in many cases it might even be said that a product is obtained which is inferior to the conventional sodium or ammonium salts. Apparently this indicates that the increased value does not reside in the additive effect in all instances of the amine residue per se. Furthermore, the effectiveness of the complex amines is not enjoyed by various other amines which at least bear some superficial analogy to the complex amines, although they are not surface-active. For instance, aniline, toluidine, propylamine, diethylamine, triethylamine, etc., cannot be substituted for the amines employed for neutralization in the preceding examples, without detracting markedly from the value of the compounds obtained. In other words, if the same alkylated naphthalene sulfonic acids which are employed to produce the chemical compound previously described, happened to be neutralized with at least certain other amines, such as those referred to, one apparently does not obtain a reagent of any marked value, and especially a reagent of any superiority or effectiveness for demulsifying oil field emulsions. Similarly, the applicants have experimented with a number of other sulfonic acids, such as certain ones derived from

petroleum, and found that neutralization with amines of the kind herein described does not give nearly as effective a reagent, in many instances, as conventional neutralization with caustic soda, caustic potash, ammonium hydroxide, and the like. Based on the results of actual tests obtained in a variety of emulsified crudes occurring in a number of the major oil fields of the United States, the conclusion one must 10 inevitably reach is, that the result obtained by uniting the two surface-active residues, i. e., the amine residue of the kind described and the sulfo-aromatic residue of the kind described, in a single molecule, is an unlooked-for unique 15 quality which could not be foreseen by the present knowledge of the art and which produces a demulsifying agent that is particularly effective for a large number of emulsified crude oils. It is obvious that certain functional equivalents 20 may be employed; for instance, hydroxy- amines characterized by the presence of a cyclohexyl radical, may be replaced by those in which an alkylated cyclohexyl radical appears. Similarly, hydroxyamines derived by the partial hy- 25 drogenation of aniline or its homologues, pro- vided that they are basic in character, may be employed in the manner previously described. Obvious functional equivalents of aralkylamines and alkylamines, previously mentioned, are well 30 known and may be employed to produce the complex amines previously disclosed in detail.

In practising our process in regard to oil field emulsions, a treating agent or demulsifying agent of the kind above described is brought into contact with or caused to act upon the emulsion to be treated, in any of the various ways or by any of the various apparatus now generally used to resolve or break petroleum emulsions with a chemical reagent, the above procedure being used 40 either alone or in combination with other demulsifying procedure, such as the electrical dehydration process.

Having thus described our invention, what we claim as new and desire to secure by Letters 45 Patent is:

1. A process for breaking petroleum emulsions of the water-in-oil type, characterized by sub- jecting the emulsion to the action of a demul- 50 sifying agent comprising a product of the kind derivable by neutralization reaction between (A) a surface-active amine of the formula type

55 in which R.COOC_nH_{2n} represents the oxy-acyl radical derived from a monobasic detergent-forming acid; T represents a hydrogen atom or a non- hydroxy hydrocarbon radical or the acylated 60 radical obtained by replacing a hydrogen atom of the hydroxyl group of an alkylol radical by the acyl radical of a monobasic carboxy acid having less than eight carbon atoms; n represents a small whole number which is less than 10; m represents the numeral 1, 2, or 3; m' represents the numeral 0, 1, or 2; and m'' represents the numeral 0, 1, or 2, with the proviso 65 that m+m'+m'' equals 3; and (B) a surface- active alkylated naphthalene sulfonic acid in 70 which at least one alkyl group substituted in the naphthalene nucleus contains at least three carbon atoms and not more than 10 carbon atoms.

2. A process for breaking petroleum emulsions of the water-in-oil type, characterized by sub- 75 jecting the emulsion to the action of a demulsify-

ing agent comprising a product of the kind derivable by neutralization reaction between (A) a surface-active amine of the formula type

in which R.COOC represents the oxy-acyl radical derived from a fatty acid having at least 8 and not more than 32 carbon atoms; T represents a hydrogen atom or a non-hydroxy hydrocarbon radical or the acylated radical obtained by replacing a hydrogen atom of the hydroxyl group of an alkylol radical by the acyl radical of a mono- basic carboxy acid having less than eight carbon atoms; n represents a small whole number which is less than 10; m represents the numeral 1, 2, or 3; m' represents the numeral 0, 1, or 2, with the proviso 10 that m+m'+m'' equals 3; and (B) a surface- active alkylated naphthalene sulfonic acid in 15 which at least one alkyl group substituted in the naphthalene nucleus contains at least three carbon atoms and not more than 10 carbon atoms.

3. A process for breaking petroleum emulsions of the water-in-oil type, characterized by sub- jecting the emulsion to the action of a demul- 20 sifying agent comprising a product of the kind derivable by neutralization reaction between (A) a surface-active amine of the formula type

35 in which R.COOC represents the oxy-acyl radical derived from a fatty acid having at least 8 and not more than 32 carbon atoms; T represents a hydrogen atom or a non-hydroxy hydrocarbon radical or the acylated radical obtained by replacing a hydrogen atom of the hydroxyl group of an alkylol radical by the acyl radical of a mono- basic carboxy acid having less than eight carbon atoms; n represents a small whole number which is less than 10; m represents the numeral 1, 2, or 3; m' represents the numeral 0, 1, or 2, with the proviso 40 that m+m'+m'' equals 3; and (B) a surface- active alkylated naphthalene monosulfonic acid in which at least one alkyl group substituted in the naphthalene nucleus contains at least three carbon atoms and not more than 10 carbon atoms.

4. A process for breaking petroleum emulsions of the water-in-oil type, characterized by sub- jecting the emulsion to the action of a demul- 45 sifying agent comprising a product of the kind derivable by neutralization reaction between (A) a surface-active amine of the formula type

50 in which R.COOC represents the oxy-acyl radical derived from a fatty acid having at least 8 and not more than 32 carbon atoms; T represents a hydrogen atom or a non-hydroxy hydrocarbon radical or the acylated radical obtained by replacing a hydrogen atom of the hydroxyl group of an alkylol radical by the acyl radical of a monobasic carboxy acid having less than eight carbon atoms; m represents the numeral 1, 2, or 3; m' represents the numeral 0, 1, or 2, with the proviso 55 that m+m'+m'' equals 3; and (B) a surface- active alkylated naphthalene monosulfonic acid in 60 which at least one alkyl group substituted in the naphthalene nucleus contains at least three carbon atoms and not more than 10 carbon atoms.

65

70

75

which at least one alkyl group substituted in the naphthalene nucleus contains at least three carbon atoms and not more than 10 carbon atoms.

5. A process for breaking petroleum emulsions of the water-in-oil type, characterized by subjecting the emulsion to the action of a demulsifying agent comprising a product of the kind derivable by neutralization reaction between (A) a surface-active amine of the formula type

in which R.CO represents the oxy-acyl radical derived from a fatty acid having at least 8 and not more than 32 carbon atoms; m represents the numeral 1, 2, or 3; and m' represents the numeral 0, 1, or 2; with the proviso that $m+m'=3$; and (B) a surface-active alkylated naphthalene monosulfonic acid in which at least one alkyl group substituted in the naphthalene nucleus contains at least three carbon atoms and not more than 10 carbon atoms.

6. A process for breaking petroleum emulsions of the water-in-oil type, characterized by subjecting the emulsion to the action of a demulsifying agent comprising a product of the kind derivable by neutralization reaction between (A) a surface-active amine of the formula type

in which R.CO represents the oxy-acyl radical derived from a fatty acid having at least 8 and not more than 32 carbon atoms; m represents the numeral 1, 2, or 3; and m' represents the numeral 0, 1, or 2; with the proviso that $m+m'=3$; and (B) a surface-active alkylated naphthalene monosulfonic acid in which at least one alkyl group substituted in the naphthalene nucleus contains at least three carbon atoms and not more than 5 carbon atoms.

7. A process for breaking petroleum emulsions of the water-in-oil type, characterized by subjecting the emulsion to the action of a demulsifying agent comprising a product of the kind derivable by neutralization reaction between (A) a surface-active amine of the formula type

in which R.CO represents the oxy-acyl radical derived from a fatty acid having at least 8 and not more than 32 carbon atoms; m represents the numeral 1, 2, or 3; and m' represents the numeral 0, 1, or 2; with the proviso that $m+m'=3$; and (B) a surface-active propylated naphthalene monosulfonic acid containing at least one and not more than four propyl radicals substituted in the naphthalene nucleus.
